UNITED STATES PATENT OFFICE.

HENRY FRANCIS BERTHERMAN, OF BOSTON, MASSACHUSETTS.

ATTACHMENT FOR CIGARETTE PACKAGES.

Application filed October 21, 1921. Serial No. 509,292.

To all whom it may concern:

Be it known that I, HENRY FRANCIS BERTHERMAN, a citizen of the United States, residing at Boston, in the county of Suffolk and State of Massachusetts, have invented certain new and useful Improvements in Attachments for Cigarette Packages, of which the following is a specification.

My invention is a cap or cover for cigarette package, designed to be applied to and locked in engagement therewith, and to become, while so engaged, a part of the package, giving shape and stiffness to the end of the package to which it is applied and preventing the collapse of the package when part of the contents is removed.

In the drawings:

Figure 1 is a perspective view showing one end of a cigarette package;

Figure 2 is a perspective view of the preferred form of one element of my attachment;

Figure 3 is a plan of the blank from which the box attachment shown in Figure 2 is formed;

Figure 4 is a plan of the blank from which the preferred form of the bolt element is formed.

Figure 5 is an edge view of the bolt element as formed and set, ready for use; and

Figure 6 is a side view, partly in section, of a cigarette pack with my attachment applied.

It is the object of my invention to supply a box or cap to be applied to the ordinary paper or tin foil package in which cigarettes are commonly enclosed, the box being formed of flexible sheet metal and being secured to the package by a bolt which penetrates and engages the package and is engaged also with the cap member, the result being that the box or cap is firmly secured to the package, of which it becomes temporarily a part, imparting a fixed shape to the package which persists after some or all of the contents have been abstracted, preventing the collapse of the paper package in use and giving better protection from destructive forces to the contents.

In the drawings I have shown the preferred form of my attachment, consisting of two elements, a box or cap, made up of a cover A, having four side wings a, a', b, b'. Formed in this cover are two apertures d and d'. The aperture, d, is designed to permit access to the contents of the pack after

the tin foil or paper exposed at, d, is removed. Aperture d', is designed to receive a bolt or connector device, l, shown in blank in Figure 4, which blank is bent upon itself and set, as shown in Figure 5. The under portion l^a of the blank being tapered in form from its free end to its junction with the main body, l.

The ordinary cigarette package is folded in at its ends as shown in Figure 1, the four sides of the package being folded over, the narrow sides first and the wide sides after, lapping over the narrow sides and one of the wide sides lapping over the edge of the other wide side (see Figure 1).

In use, the box member is applied to one end of the cigarette pack, the wings a, a', b, b', being, if desired, bent slightly outward, during the application and, when the box has been forced down until the underside of the end section A, contacts with the end of the pack, the bolt l is then applied to secure the box and pack together. This is accomplished by spreading apart the ends l, l^a, of the bolt slightly and inserting the end l^a into the aperture d' and passing it below the over-lapping ends p, p', of the pack P and over the end p² and forcing the bolt inward to a stop, the member l passing along the outer surface of the end piece A. The thickness of the material of the overlapped ends p, p', of the pack is sufficient to hold the parts l and l^a separated under some tension, causing the members, l, l^a, to frictionally engage the opposed surfaces, holding the bolt l in position until designedly removed.

When the parts are thus engaged the tin foil or paper beneath aperture, d, is removed and the contained cigarettes may then be removed as required. So long as the attachment remains connected with the package the package will retain substantially its shape, without collapsing and will afford all necessary protection to the contents, to the last cigarette, preventing them from being bent and crushed.

I have shown my cap or box member as of four sides; this is the preferred form, as it gives support and fixity to the cigarette pack on every side, but it is not essential, as one or both of the end wings, b, b', may be omitted if desired, and the cap will nevertheless perform its function. It is obvious that when the wings b, b', are omitted, the apertures d, d', are not essential as the ciga-

lettes may be removed through the side of the pack and the bolt or pin l , l^a , applied at either end of the part A.

I claim:

- 5 1. In a device of the character described, a cap member, adapted to enclose one end of a cigarette pack, or the like and having an aperture therein, and a forked bolt member one leg passing through the aperture and 10 cooperating with the cap member to connect the cap member to the pack.

2. In a device of the character described, a cap member, adapted to enclose one end of a cigarette pack, or the like, and having an aperture therethrough to receive a bolt member and a second aperture to permit access to the end of the pack; that bolt member, co-operating with the cap member to connect the cap member to the pack. 15

Signed at Fall River, Massachusetts, this 20
17th day of October, 1921.

HENRY FRANCIS BERTHERMAN.
